UNITED STATES PATENT OFFICE

104,396

DESIGN FOR A BOTTLE

William Fehr, Sacramento, Calif., assignor of one-fourth to Frank T. Hoffman, Sacramento, Calif.

Application January 29, 1937, Serial No. 67,337

Term of patent 14 years

To all whom it may concern:

Be it known that I, William Fehr, a citizen of the United States, residing at Sacramento, in the county of Sacramento and State of California, have invented a new, original, and ornamental Design for Bottles, of which the following is a specification, reference being had to the accompanying drawing, forming part thereof.

I claim:

The ornamental design for a bottle, as shown.

WILLIAM FEHR.
